UNITED STATES PATENT OFFICE.

JOHN A. SCHMITT, OF COLUMBUS, OHIO, ASSIGNOR TO THE UNIVERSAL MILKING MACHINE COMPANY, OF WAUKESHA, WISCONSIN, A CORPORATION OF WISCONSIN.

PULSATATOR.

Application filed February 25, 1922. Serial No. 539,167.

My invention relates to pulsators or alternators for milking apparatus and analogous purposes.

The present application is a continuation in part of my prior Patents No. 1,408,036 issued Feb. 28, 1922, and No. 1,647,971, issued November 1, 1927.

The object of the invention is to simplify the structure as well as the means and mode of operation of pulsators, or alternating devices, whereby they will not only be cheapened in construction, but will be positive in operation, uniform in action and unlikely to get out of repair.

A further object of the invention is to provide a small compact structure, having an improved method of controlling the valve mechanism, the tumbler mechanism for the control valve being actuated by the movement of the pulsator valve.

With the above primary and other incidental objects in view as will more fully appear in the specification, the invention consists of the features of construction, the parts and combinations thereof and the mode of operation or their equivalents as hereinafter described and set forth in the claims.

In the accompanying drawing, wherein is shown the preferred, but obviously not necessarily the only form of embodiment of the invention, Fig. 1 is a top plan view and Fig. 2 a side elevation of the assembled pulsator or alternator forming the subject matter hereof. Fig. 3 is a top plan view partly in section of the main structure with the valve mechanism removed. Fig. 4 is a vertical sectional view of the main structure shown in Fig. 3. Fig. 5 is a perspective view of the reciprocating pulsator valve viewed from the under side. Fig. 6 is a bottom plan view of the alternating valve mechanism. Figs. 7 and 8 are detail sectional views, illustrating the interconnection of the valved ports.

Like parts are indicated by similar characters of reference throughout the several views.

The structure herein shown is particularly adapted for being mounted upon the lid or cover of a pail or receiver, which will form the closure of the bottom vacuum chamber contained in the base of the structure. Otherwise the pulsator is mounted upon a suitable base, not shown, in lieu of such pail

or receiver lid. In the particular form of embodiment illustrated, the pulsator comprises a vertically disposed cylindrical chambered base 4, carrying at one side thereof a laterally disposed integral short cylinder 5, and adjacent to this cylinder 5 and forming the top of the base 4 or vacuum chamber is a flat table like valve bearing surface 6. Upon this bearing surface or valve table 6, the pulsator and control valve are preferably mounted. The vacuum chamber 7 within the base 4 is provided with a nipple or spud 8, through which it communicates with any source of suction such as a vacuum tank a pump or other such device. The head of the base 4 immediately beneath the valve bearing surface is provided with a transverse bore 9, communicating with the interior of the cylinder 5, and within which bore reciprocates a piston stem 10, connected within the cylinder 5 to a piston head. The piston head is actuated to and fro by alternation of atmospheric pressure on opposite sides thereof. It comprises two oppositely disposed tapered discs 11, between which is disposed an annular collar or ring 12 of packing material, such as leather, rubber, composition or other suitable substance. By relative adjustment of the tapered disc 11 by means of a clamp nut 13, upon the extremity of the piston rod, the annular packing 12 may be subjected to greater or less compression and so expanded into engagement with the walls of the cylinder 5.

The piston is actuated to and fro by alternately connecting the opposite sides of the piston with atmosphere and with the suction or vacuum chamber 7 respectively. To this end the valve table 6 is provided with a group of three ports, 17, 18 and 19. The intermediate port 17 extends downwardly through the head or top of the pulsator body and communicates at its lower end with the vacuum chamber 7, which in turn is directly connected by a nipple or spud 8, with a source of suction. The port 18 communicates through a lateral passage 18', shown by dotted lines, with the inner end of the cylinder 5. The remaining port 19 is likewise connected through a communicating passage 19' with the outer end of the cylinder 5 and beyond the piston head. These ports are controlled by an oscillatory control valve 20, pivotally mounted upon a

stud 21, and oscillated to and fro to alternately connect the suction port 17 with the respective ports 18 and 19. The disconnected port being uncovered by the movement of the valve 20 admits air at atmospheric pressure to the cylinder. At the same time, the opposite end of the cylinder is connected through the corresponding passage and port with the vacuum chamber 7. As a result the atmospheric pressure upon the piston head will shift the piston toward the end of the cylinder connected with the suction or vacuum chamber. This movement of the piston is transmitted to the valve 20 to reverse the position of the valve and the communication of the ports controlled thereby to admit air pressure to the opposite side of the piston 10 and reversing the connection of the cylinder 5 with the suction or vacuum chamber 7. Adjacent to the opposite side of the valve table 6 is a second group of ports 23, 24 and 25, constituting the pulsator ports and controlled by the reciprocating pulsator valve 26. The intermediate port 23 communicates with the vacuum chamber 7, while the ports 25 and 26 are independently connected with a separate teat cup connection in this instance a Y-connection 27. The teat cup clusters are connected with the connections 27, and alternately actuated as the valve 26 is reciprocated.

The pulsator valve 26 is recessed on its under side at 26' to afford an intercommunicating passage between the intermediate port 23 and the respective ports 24 and 25 when the valve is at the opposite limit of its stroke. At one limit of its movement the valve 26 connects the ports 23 and 24 leaving the port 25 open to atmosphere while at its opposite stroke this connection is reversed, opening the port 24 to atmosphere and connecting the port 25 with the source of suction through the port 23.

The valve 26 is slotted or splined on its under side as at 28 for engagement over a feather or gib 29, projecting from the top surface of the valve table 6. This guide feather or gib 29 may be integral with the pulsator body, or may be separately formed and secured thereto. The table top 6 is finished with a uniform smooth surface over which the control and pulsator valve plays. The bearing surfaces of the valves upon the table are such as to form hermetically sealed contacts excluding atmospheric air.

In the table surface 6 there is formed a slot 6^a communicating with the bore 9. The piston stem 10 extending within the bore 9 carries a stud 10^a, which projects above the face of the valve table 6, through said slot 6^a, and engages a socket or hole 26^a in the under side of the reciprocating pulsator valve 26. The valve 26 thus rests loosely upon the bearing or table surface 6, and is pressed thereon by atmospheric pressure, the

underside of the valve, particularly the recess 26" being subjected to suction or vacuum. Thus atmosphere forms a preponderance of pressure upon the top of valve holding it to its bearing upon the surface 6. The same is true of the control valve 20, which likewise is subjected to suction or vacuum on its under side through the port 17, while atmosphere affords a preponderance of pressure upon the top. The pulsator valve 26 being connected with the piston 10 thru the stud 10^a and piston stem 10, reciprocates in unison with the piston and alternates the connection of the teat cup spuds 27 with the suction or vacuum chamber 7. This movement of the pulsator valve alternately subjects each of the teat cup spuds 27 to admission of air at atmospheric pressure and to exhaust through connection with the vacuum chamber 7.

This to and fro movement of the pulsator valve is transmitted to the control valve 20 to affect its alternation as the pulsator valve and with it the piston 10 approach the limit of their movement in either direction. The alternation of the control valve 20 in turn admits actuating fluid i. e. air at atmospheric pressure, alternately to opposite sides of the piston head. In the present instance the construction is such that the control valve 20 is automatically locked in its operated position until the pulsator valve and piston approach the opposite limits of their stroke whereupon the control valve is not only unlocked, but is actuated with a snap over movement to its reverse position.

To this end, there is pivoted upon the table 6 an oscillatory actuating head 30, having in one side thereof two intersecting arcuate faces 31—31. This actuating head 30 is provided with a dependent pin or stud 32, which engages in a bifurcation 32' in the oscillatory control valve 20. By the to and fro oscillation of the actuating head 30, about its pivotal stud 34, the control valve 20 is oscillated in unison to cover and uncover the ports 18 and 19 alternately. Pivoted upon the table 6 intermediate head 30 and reciprocating pulsator valve 26 upon a pivotal stud 35 is an oscillatory locking arm 36. This locking arm 36 is provided with a stop nose 37, which engages alternately in the respective arcuate faces 31 of the head 30, according to the position of the head. These arcuate faces 31 of the actuating head 30 are so arranged as to be concentric with the pivotal stud 35 of the locking lever, when the head 30 is at the opposite limit of its oscillatory movement. That is to say, when the head 30 is turned in one direction, one of these arcuate faces 31 will be positioned concentric with the pivotal stud 35, and in position to be uniformly engaged by the locking nose 37 of the lever 36. Upon reversal of the actuating

head 30, the opposite arcuate face 31 will be likewise engaged by the nose 37 of the lever 36. The locking lever 36 is provided with a dependent stud 38 which engages within a notch or recess 39 in the upper face of the reciprocating pulsator valve 26. By this means the lever 36 is oscillated to and fro in unison with the reciprocation of the pulsator valve and the piston. A spring 40 is connected at one end to a stud or other connection 41, at the free end of the locking lever 36, and connected at its opposite end eccentrically with the head 30. In the present instance this eccentric connection of the head 30 has been shown as by means of a wire bail 42, which is bent laterally to form an offset connection for the spring and afford the necessary leverage for oscillating the actuating head. Any suitable connection may be employed as an arm or finger extended a sufficient distance to afford the requisite leverage to oscillate the actuating head 30. As the piston and pulsator valve moves to and fro the locking lever 36 is oscillated in unison to afford a winding movement of the locking nose 37 within the concentrically positioned arcuate face 31. The engagement of the nose 37 within such arcuate face serves to hold the head 30 against oscillation under the influence of the spring 40 after said spring has passed a dead center position in the movement of the lever, until the locking nose 37 has passed out of the particular arcuate face or beyond the juncture of the two faces 31. The parts are so proportioned that this locking nose will pass this juncture angle of the arcuate faces 31 only as the piston and pulsator valve 26 approach the limit of their stroke. At this time the movement of the locking lever 36 has placed the spring 40 under tension and the spring will in turn be exerting a pulling influence upon the laterally disposed wire bail or lever 42. The retraction of the spring 40 as the nose 37 passes beyond the juncture angle of the faces 31 serves to oscillate the head 30 and through the interconnection of its dependent pin or stud 32 within the bifurcation 33 of the control valve, it oscillates the control valve 20 about its stud 21, thereby reversing the atmospheric and suction influences upon the piston and the parts begin their travel in the opposite direction. Upon approaching the limit of stroke in the reverse direction the same cycle of operation is repeated. Thus the movement of the lever 36 to and fro past a dead center position, in relation with the center of oscillation of the actuating head 30, tensions the spring 40 to actuate the head 30, first in one direction and then in the other when released for such oscillatory movement by the travel of the nose 37 of the locking lever 36 beyond the juncture angle of the faces 31. The speed with which the alternation or reversal occurs is controlled by regulating the capacity of the control port 17. To this end there is provided an adjusting screw 43 which intersects the port passage and by its adjustment serves to reduce the capacity of the port and hence the volume of air passing therethrough and so retards the speed of operation. The entire tumbler mechanism and valve may be enclosed within a suitable cap or housing which may be mounted upon the top of the structure shown.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is therefore claimed in any of its forms or modifications within the legitimate and valid scope of the appended claims.

Having thus described my invention, I claim:

1. In a snap over mechanism of the character described, the combination with a body having ports to be alternately opened and closed, of a movable valve member controlling said ports, an oscillatory actuator head mounted independent of said valve, having intersecting arcuate faces, and an operative connection with the port control valve, an oscillatory stop member having wiping engagement with the arcuate faces of said actuator head, said arcuate faces being alternately brought into concentric relation with the pivotal connection of the oscillatory stop member, said stop member locking the actuator head against reversal until the stop member has moved through a prescribed limit of travel and means for actuating the stop member and means to reverse said head when released by said stop member.
2. The combination with fluid pressure operated pulsator mechanism, of a pivoted control valve governing the action of the fluid pressure upon said mechanism, tumbler mechanism for automatically reversing said valve, including an oscillatory head eccentrically pivoted in relation with the pivotal mounting of the valve, but operatively connected with the valve and having two intersecting arcuate faces, an oscillatory stop

member with the pivotal connection of which the arcuate faces are concentrically positioned alternately, means for periodically oscillating said actuating head and means for actuating the stop member to release said head for periodic oscillation by which the control valve will be simultaneously oscillated.

3. The combination with fluid pressure operated pulsator mechanism, of a movable valve member, an oscillatory actuator head pivoted independent of, but operatively connected with the movable valve, a pivoted stop member, two arcuate faces on said head alternately moved into concentric relation with the pivot of said stop member by the reversal of said head, means for periodically reversing said head and with it the valve and means for actuating the stop member to release the head for such reversal.

4. In a construction of the character described, a movable valve member, an oscillatory stop member, and a separately pivoted actuator head operatively connected with said valve and having thereon two arcuate faces engaged alternately by said stop member, and alternately positioned concentric with the center of oscillation of the stop member by the pivotal movement of the head, means for periodically reversing said head, and means for actuating the stop to disengage it from one arcuate face to permit the movement of the head which brings the other arcuate face to position to be engaged.

5. The combination with a fluid pressure operated pulsator mechanism, of an intermittently movable control valve governing the action of the fluid pressure, a movable pulsator valve actuated by the pulsator mechanism, an operative connection for transmitting motion from the pulsator valve to said control valve and an oscillatory stop member actuated by and movable to and fro about a pivotal center in unison with the movement of the pulsator valve for releasably holding the control valve against movement until the pulsator valve has reached the limit of its travel.

6. In a construction of the character described, a fluid pressure operated piston, a pulsator valve directly connected with the piston for movement therewith, a movable control valve governing the action of the fluid pressure upon said piston, a spring energized by the movement of the pulsator valve to actuate the control valve and a

governor therefor comprising an oscillatory head pivoted for movement through a path of travel different from that of the valve having two arcuate faces and an oscillatory stop member alternately engaging said faces with the pivotal connection of which the arcuate faces are alternately concentrically positioned by the oscillation of the head, an operative engagement between said head and control valve and an operative connection between said stop member and the pulsator valve.

7. In a construction of the character described, a fluid pressure operated piston, a valve governing the action of the fluid pressure upon the piston, an oscillatory control head mounted independent of said valve but operatively connected therewith, a movable stop member alternately holding the control head in different positions of adjustment, means for periodically reversing said head and means for actuating the stop member to release said head for reversal.

8. In a fluid pressure operated pulsator mechanism, a travelling pulsator valve, means for controlling the action of the fluid under pressure to effect reciprocatory reversal of direction of movement of the valve at opposite limits of its stroke, a pivoted stop member having operative connection with the pulsator valve for oscillatory actuation thereby, and an oscillatory member having two arcuate faces alternately positioned concentric with the center of oscillation of the pivoted stop member within which arcuate faces the stop member performs a sweeping movement while holding the oscillatory member against reversal until the stop member passes beyond the limit of the engaged arcuate face, and means for oscillating said member having the arcuate faces to effect a reversal of the action of the fluid pressure upon the pulsator valve.

9. A fluid pressure operated pulsator mechanism including a reciprocatory pulsator valve, an oscillatory control valve governing the action of the fluid under pressure, to reciprocate the pulsator valve, an oscillatory stop lever actuated to and fro by the movement of pulsator valve and preventing the movement of the control valve until the pulsator valve reaches the limit of its stroke.

In testimony whereof, I have hereunto set my hand this 21st day of February A. D. 1922.

JOHN A. SCHMITT.
